CHARLES C. ROSSOTTI, OF NEW YORK, N. Y., ASSIGNOR TO ROSSOTTI LITHOGRAPHING COMPANY, INC., OF NEW YORK, N. Y., A CORPORATION OF NEW YORK

DISPLAY CONTAINER

Application filed February 11, 1932. Serial No. 592,380.

This invention relates to display cartons of the type having a window through which part of the contents of the carton are visible for purpose of display.

5 The object of the invention is to provide a carton having a display aperture cut in one face thereof, said carton being enclosed in a wrapper completely sealed against the entrance of dust, and having a window glazed 10 with a transparent membrane and register- ing with the aperture in said carton.

It is old in the art to provide a carton particularly of the one-piece tuck flap type, having a display aperture covered by a sheet of 15 cellophane or other transparent membrane, pasted on from the inside of the carton. This construction has heretofore been applicable only to an unwrapped carton, and this type of carton is open to the serious objection that 20 it is not dust-proof.

In the quest for a dust-proof display pack- age, manufacturers and distributors have adopted a carton having a display opening, the carton being completely wrapped within 25 a transparent sheet through which the dis- play opening and the contents of the package are visible. This answers the desideratum of dust-proofness, but it is not only expensive, but has the much more important drawback, 30 that the transparent wrapper obscures the printing and color lithographed on the car- ton, so that the transparent wrapper becomes the predominant feature of the package, the brand becoming a secondary or sub-ordinate 35 characteristic. This is explained through the fact that the transparent wrapper does not fit closely against the surfaces of the carton so that a thin film of air intervenes, which causes total reflection of light from the 40 wrapper or at least a part thereof, detracting from the visibility of the brand.

The present invention seeks to avoid this 45 drawback by providing an opaque wrapper for completely enclosing the carton upon which the printing and color of the litho- graphing may appear, and having a trans- parent window adapted to register with an opening in the carton, when the wrapper is applied to the carton.

50 Other objects of the invention will appear

as the following description of a preferred and practical embodiment thereof proceeds.

In the drawing throughout the several figures of which the same characters of reference have been employed to denote identical 55 parts:

Figure 1 is perspective view of the carton;

Figure 2 is a plan view of the paper wrap- 60 per in flat position showing the cellophane sight or window;

Figure 3 shows the first stage in the wrap- 65 ping of the carton, the ends of the wrapper being extended, and showing slits to facilitate the folding of the wrapper about the ends;

Figure 4 is a similar view, the fold being partly completed;

Figure 5 is a similar view showing a stage 70 in the sequence of the wrapping operations, in which the upper end flap is about to be pasted into dust-sealing relation upon the folded end of the wrapper;

Figure 6 is a perspective view showing the 75 end of the wrapper in its finished, sealed state; and

Figure 7 is a cross section through the 80 wrapped carton showing the glazed aperture of the wrapper in registry with the open aperture in the face of the carton.

Referring now in detail to the several fig- 85 ures, the numeral 1 represents a carton. In the illustrative embodiment as shown, this is composed of a unitary blank of sheet material such for instance, as pasteboard suitably folded and slotted to form a carton of the known tuck-flap type. It has an aperture 2 formed in one face, in the present instance, in the top. The carton completed to the extent as shown in Figure 1 is filled with the prod- 90 uct to be packaged and the lid closed in the customary manner.

In Figure 2 is shown the wrapper which 95 comprises a flat sheet 3 of any suitable opaque material such, for instance as an ordinary light grade of paper. It may be printed, or lithographed in color and to show the brand, and it is provided in a suitable region with an aperture 4 glazed with a small sheet 5 of transparent membrane adhesively applied to the underside of the wrapper.

In practice, the wrapper is laid down upon the filled and closed carton by a machine with sufficient precision to cause the aperture 4 in the wrapper to register with the aperture 2 in the top of the carton. The wrapper is then folded around the carton in conformation to the surface thereof, the lines of fold being shown in broken lines in Figure 2. The edge 6 is overlapped by the bottom face 10 7 and is adhesively joined thereto. The ends of the carton are folded together in known manner, slits 8 being cut in the wrapper to facilitate folding. The lower end flap 9, see Figure 3, is first folded upward into a 15 position against the end of the carton as is indicated in Figure 4. The triangular extending side portions 10 thus formed are folded flat against the ends of the carton as is indicated in Figure 5. This leaves only 20 the extended portion of the top face of the wrapper free. This portion forming the flap 11 is now folded down and pasted against the flap 9 and the portions 10, completely sealing the ends of the carton.

25 As has been stated in connection with the objects of the invention, this is the first instance insofar as is known in which the idea of the glazed display window has been applied to an opaque wrapper of the dust-proof 30 type in which the printing, coloration or brand of the package is exposed in all its brightness without any diminution in its appearance such as is ordinarily caused when the carton is enclosed in a transparent wrapper.

35 While I have in the above description described what I believe to be a preferred and practical embodiment of the invention, it is to be understood that the illustrative embodiment of the invention as shown is merely by way of example, but that the principles of the invention can be applied to a carton of any shape and construction, the inventive concept being satisfied by the provision in a 40 dust-proof wrapper of the glazed window registering with an open window or aperture in the carton itself.

45 What I claim is:

Dust sealed package with display window 50 comprising a carton of material sufficiently stiff to be self-shape retaining having a window opening in a face thereof, an opaque flexible wrapper having a window opening, a transparent membrane glazing said last 55 named opening, said wrapper being positioned in enclosing and fitting relation to said carton with its glazed opening registering with the opening in said carton and its sealing edges overlapping and adhesively 60 united.

In testimony whereof I affix my signature.
CHARLES C. ROSSOTTI.
